UNITED STATES PATENT OFFICE.

HERBERT E. VAN DORN, OF CHICAGO, ILLINOIS.

RAILWAY DRAWBAR.

Application filed February 16, 1927. Serial No. 168,609.

The present invention relates to draft rigging for railway cars, of the types in which the coupler head is permitted to oscillate about a longitudinal axis, or the coupler head is adapted to swing in a horizontal plane about a remote center, or the drawbar shank or similar part is adapted to slide longitudinally a limited distance through a suitable carrier, or any combination of such types; and its object is to simplify and improve the construction thereof.

In my prior Patent Number 1,524,679, granted February 3, 1925, I have disclosed a drawbar construction embodying all of 15 the features of the several types enumerated above and, viewed in a specific aspect, the present invention may be said to have for its object to improve on that construction.

The various features of novelty whereby 20 my invention is characterized will herein-after be pointed out with particularity in the claims; but, for a full understanding of my invention and of its objects and advantages, reference may be had to the following detailed description taken in connection with the accompanying drawings, wherein:

Figure 1 is a longitudinal section through 30 a drawbar and support embodying the present invention, only so much of the old structure being shown as is needed to illustrate the invention; Fig. 2 is a section on line 2—2 of Fig. 1; Fig. 3 is a detail showing a slight modification; Fig. 4 is a front 35 elevation, on a larger scale, of the main bar or strut; and Fig. 5 is a section on line 5—5 of Fig. 4.

Referring to the preferred embodiment of 40 my invention illustrated in the drawings, 1 represents a long strut or bar the body portion of which is inclined upwardly and rearwardly; the rear end being adapted to be connected to a car frame by being pivoted to a suitable spring draft gear, not shown, as in my prior patent or otherwise. The front end of the member 1 taken the form 45 of a housing 2 open at the front and rear ends and having a cylindrical interior. The part 2 extends through a carrier consisting 50 of an inverted U-shaped member 3 between the lower ends of whose arms is secured a shoe 4, preferably by means of two bolts 5 passing through the same and through the arms of the carrier. When there is a spring 55 connection between the drawbar and the car

frame, permitting the drawbar to slide through the carrier, wear occurs on the shoe 4 or the shell 2 or both. To compensate for this wear and make it unnecessary to replace either because of wear, I secure to the underside of the housing 2 a wearing plate 6 and/or to the top of the shoe a wearing plate 7, the plate or plates being detachable to permit replacements to be easily made.

The carrier has a T slot 8 running across 65 the top of the same on an arc struck about the pivotal connection of the drawbar with the car as a center. The carrier is slidably supported on a flat curved bar 9 extending through the horizontal portion of the slot 70 in the top of the carrier; the bar being in turns hung from the underside of the car by means of bolts 10 passing through suitable spacing bushings or sleeves 11. This arrangement permits the drawbar to swing 75 bodily about a vertical axis at the rear while free to move radially, that is in the direction of its length, through the carrier.

The coupler head, not shown, is adapted to be supported on the front end of a stem 80 12 so as to be capable of swinging about a vertical axis. This may be accomplished by passing a pin through registering holes 13 in two ears 14 located at the front end of the stem on opposite sides of the longitudinal axis. The stem comprises a cylindrical part 15 fitting into the housing 2. The stem is enlarged at the front end to form an abrupt shoulder 16 adapted to bear against a machined face at the front end of the 90 housing. The rear end of the housing, also, is machined. The rear end of the stem terminates in a screw-threaded element 17 on which is a nut between which and the rear end of the housing is a washer 19. It will 95 thus be seen that the stem is fitted into the housing in such a manner that it may turn therein, but is securely held against any other movement of any kind relative to the housing.

While the stem for supporting the coupler head may turn, yet the coupler head should normally be horizontal and upon uncoupling should be returned to that position if not already there. To this end I have provided 105 a novel device that yieldingly holds the stem in such a position that the pivotal axis of the coupler head is horizontal, thus causing the coupler head to be held normally in a horizontal position. This device consists of a 110

frame-like casting 20 situated between ears 21 and 22 on the underside of the front end of the housing; the width of the casting being considerably less than the distance between such ears. A bolt 23 passes through the ears and the intervening casting. There are on the bolt two followers 24 in the form of sleeves extending through the side members of the frame and abutting at their outer ends against the ears 21 and 22, respectively. The sleeves have flanges 25 at their inner ends. Surrounding the bolt 23, between the sleeves, is a spring 26 under an initial compression. This spring tends constantly to press the followers apart and hold them in contact with the ears on the drawbar. The followers, acting on the frame-like casting through their flanges, therefore tend to hold this member centered and to return it to a central position whenever it is displaced laterally in either direction. The casting 20 has at its front end two separated lugs 27 lying on opposite sides of the longitudinal axis of the structure and, lying between these lugs is an ear 28 fixed to a forming part of the stem 12. When the stem turns in either direction, the ear 28 engages with one of the lugs on the frame-like casting and pushes this casting sidewise against the resistance of the spring. When the forces that hold the stem twisted out of its normal position are removed the spring pushes the frame back into its normal central position, one of the lugs acting on the ear on the stem to turn the stem back to its normal position.

The stem 12 will usually be a casting and it may therefore happen that the screw threaded part 17 will not be sufficiently sound to serve its purpose, even though the item be otherwise satisfactory. I have therefore shown in Figure 3 a means for securing the stem into the drawbar by means of an added stud. This stud, indicated at 30, is screwed into a socket 31 in the rear end of the stem, and is anchored by means of a pin 32 passing through the same and through the stem. The nut and washer, 18 and 19, are placed on this stud just as, in Fig. 1, they are positioned on the screw-threaded projection 17 integral with the stem.

While I have illustrated and described with particularity only a single preferred

form of my invention, I do not desire to be limited to the exact structural details thus illustrated and described; but intend to cover all forms and arrangements which come within the definitions of my invention constituting the appended claims.

I claim:

1. In combination, a drawbar having at its front end a housing provided with a longitudinal bore extending through the same, a cylindrical stem fitted in said bore so as to be rotatable therein, means at the front end of the stem for supporting a coupler head, a shoulder on the stem engaged with the front end of the housing, a stud screwed into the rear end of the stem, a pin extending transversely through the stem and stud, and a nut on the stud bearing against the rear end of the housing.

2. In combination, a drawbar, a stem extending into and rotatable in the front end of the drawbar, two abutments on the underside of the front end of the drawbar on opposite sides of the longitudinal center, a member mounted between said abutments and movable laterally a limited distance between the same, a spring means tending constantly to hold said member centered, and there being an interlock between said member and said stem to cause oscillatory movements of said stem to be accompanied by reciprocating movements of said member.

3. In combination, a drawbar, a stem extending into and rotatable in the front end of the drawbar, two abutments on the underside of the front end of the drawbar on opposite sides of the longitudinal center, a frame-like member narrower than the distance between said abutments lying between the latter, a bolt passing through said abutments and through the frame so as to cross the opening in the frame, flanged sleeves surrounding the bolt and each passing through one of the side elements of the frame and engaged with the corresponding abutment, a compression spring between said sleeves, and shoulders on the frame and the stem to cause an oscillatory movement of said stem to be accompanied by a reciprocatory movement of said frame.

In testimony whereof, I sign this specification.

HERBERT E. VAN DORN.
